UNITED STATES PATENT OFFICE

FLORICEL A. STAPLER, OF PHILADELPHIA, PENNSYLVANIA, ASSIGNOR TO VICTOR
TALKING MACHINE COMPANY, A CORPORATION OF NEW JERSEY

MEMBER OR STRUCTURE VIBRATED BY ENERGY IMPULSES

Application filed October 10, 1928. Serial No. 311,554.

My invention relates to a member or structure partaking of vibratory motion under the influence of energy impulses having a frequency, usually, varying between 16 and 20,000 cycles per second or those having a frequency of the order usually encountered in speech or music transmission.

10 My invention relates to a member or structure, as aforesaid, utilized to transmit or transfer energy impulses, as aforesaid, from one region to another or from a transmitting member to a receiving member.

15 My invention relates to a member or structure, as aforesaid, as an arm or bar to which vibratory motion is imparted by a transmitting member or system, as a phonograph record or a magnetic structure, the energy impulses actuating or controlling a suitable receiving member or system, as a diaphragm, 20 armature, or the flux in a magnetic circuit.

25 In accordance with my invention, the configuration of each of a plurality of blanks is changed to produce dissimilar structures which are thereafter secured together to form a member or structure, as aforesaid.

Further in accordance with my invention, the aforesaid blanks are formed from sheet material having different thicknesses.

30 Further in accordance with my invention, each of the aforesaid blanks is shaped to produce a body portion having lateral wings, the wings of one body portion reinforcing the wings of another body portion.

35 More particularly, in accordance with my invention, the aforesaid wings of one of said shaped blanks are folded or bent around portions only of the wings of another of said shaped blanks to thereby produce a hinge structure.

40 Further in accordance with my invention, resilient members of sheet material are disposed on each side of a member or structure, as aforesaid, to form a hinge support therefor, said resilient members, ordinarily, being disposed in a single plane.

45 In accordance with one important phase of my invention, the aforesaid member or structure is an arm or bar carrying, at one end, a stylus or needle, the other end thereof being connected to a sound-producing dia-

phragm. The detailed description following hereafter refers to a construction of the character last described, although it shall be understood that my invention is not to be thus limited.

55

My invention resides in the member or structure, article, method, and features of construction of the character hereinafter described and claimed.

For an illustration of some of the forms 60 my novel member or structure or article may take and for an understanding of my method, reference is to be had to the accompanying drawings in which:

Figures 1 and 2 are plan views, respectively, of stampings or blanks destined to form a single needle arm.

Fig. 3 and 4 are perspective views, respectively, of shaped blanks produced from the blanks of Figs. 1 and 2.

70

Fig. 5 is a perspective view of a needle arm produced by assembling the shaped blanks illustrated in Figs. 3 and 4.

Fig. 6 is a vertical sectional view, partly in elevation, of my novel needle arm or stylus 75 bar and associated parts of a sound box.

Fig. 7 is a vertical sectional view, partly in elevation, of the stylus-carrying end of my needle arm.

Fig. 8 is a transverse horizontal sectional 80 view taken on the line 8—8 of Fig. 6 and looking in the direction of the arrows.

Fig. 9 is an enlarged horizontal sectional view of the stylus-carrying end of my needle arm.

85

Fig. 10 is a perspective view of another form of needle arm constructed in accordance with my invention.

Referring to Figs. 1 and 2, there are illustrated two blanks B and B1 destined, 90 after proper shaping operations, to be secured in assembled relation for forming a stylus bar or needle arm. The aforesaid blanks, ordinarily, are stamped from sheet material and, as illustrated in Figs. 1 and 95 2, are substantially or entirely plane in configuration.

To shape the blank B, it may be bent or folded along lines substantially as indicated by the broken lines 1, 1 Fig. 1, to produce 100

the tapered walls or members *a*, *a*, Fig. 3, joined by a base substantially arch-shaped in cross-section and from which a member *b* extends. To further shape the blank B, it may 5 be bent or folded along lines substantially as indicated by the broken lines 2, 2, Fig. 1, to produce the wing members *c*, *c*, Fig. 3, extending in opposite directions from one another in a single plane, in the example shown, 10 and disposed substantially at right angles to the respective members *a*, *a*.

The blank B1 is bent or folded along lines substantially as indicated by the broken lines 3, 3, Fig. 2, to form substantially one-half 15 of said blank B1 as a section comprising the walls *d*, *d* joined by a base substantially arch-shaped in cross-section. To further shape the blank B1, it is bent or folded along lines substantially as indicated by the broken 20 lines 4, Fig. 2, outlining a Y-shaped figure, to form substantially one-half of said blank B1 as a section comprising a substantially triangular opening or chamber *e*, Fig. 9, to one side of which are the blank walls *f*, *f* 25 disposed adjacent each other and in contacting relation, or substantially so. To still further shape the blank B1, it is bent or folded along lines substantially as indicated by the broken lines 5, 5, Fig. 2, to produce the 30 wing members *g*, *g* extending in opposite directions from one another in a single plane and disposed substantially at right angles to the respective walls *d*, *d*.

After the blank B1 has been shaped as described above, the walls *f*, *f* are suitably united, preferably by a welding operation as indicated by the cross-hatching in Fig. 7. Thereupon, the structure formed by said walls *f*, *f* is provided with a threaded passage 35 communicating with the aforesaid chamber *e* and receiving the threaded shank of a screw *h* which binds or retains one end of a needle or stylus *i* within the chamber *e*. Ordinarily, movement of said needle or stylus *i* in one 40 direction within the chamber *e* is limited by a stop *j* suitably formed therein, the operative end of said needle or stylus projecting from said chamber for coaction with a talking machine or phonograph record, not 45 shown.

To assemble the shaped members B and B1, the section of the latter defined by the walls *d*, *d* is disposed within the walls *a*, *a* of blank B to produce the composite structure 50 or needle arm illustrated in Fig. 5, adjacent parts of the respective members being suitably united, as by a soldering operation. The parts are so proportioned that substantially one-half of each wing *g* assumes a position 55 immediately adjacent one side of each wing *c* while the other half of each wing *g* extends beyond each wing *c*. The last named parts, 60 namely, the exposed sections of the wings *g* are then bent around until U-shaped and immediately adjacent the opposite sides of the 65

respective wings *c* and, in this position, the folded wings *g* are soldered, or otherwise suitably secured to the respective wings *c*.

A needle arm or stylus bar of the character hereinbefore described is illustrated in Fig. 6 as forming part of a talking machine or phonograph sound box. This sound box may be of any suitable or desired character and in Fig. 6 is illustrated as comprising a base section 10 terminating in a tubular conduit 10a adapted to be associated with the tone arm of a sound amplifying horn. A diaphragm 11 of any suitable character which, however, in the example illustrated is of the type illustrated in my co-pending application Serial No. 311,553 filed Oct. 10, 1928, is received at its peripheral edge between washers 12, 12, a cap member 13 cooperating with a ring 14 threaded thereto to retain the diaphragm 11 in the position illustrated in Fig. 6. One side of the cap member 13 may be skeleton-like, by virtue of which one side of the diaphragm 11 is placed in direct communication, through a plurality of passages, with the surrounding atmospheric medium. 80 On the side of the diaphragm 11 facing the conduit 10a, there may be disposed a plug or member 18 for producing properly dimensioned paths for the propagated sound waves. 85

In the example illustrated, the composite 90 needle arm of stylus bar is secured to the diaphragm 11 only at the mid-point thereof, the member *b* constituting a tie member between the needle arm proper and the diaphragm, said member *b*, in the example 100 shown, passing through a bushing disposed centrally of the diaphragm and being suitably secured thereto, as by a mass of wax or solder, not shown.

The wings *c* constitute the hinging or pivotal support for the needle arm or stylus bar and they may be supported in any suitable manner. To this end, in the example shown, the cap section 13 is provided with the lugs or members 15 projecting laterally therefrom, 110 each of the aforesaid wings *c*, *c* being received between one face of a lug 15 and a plate or member 16. In the example shown each wing *c* is provided, during the stamping operation, with a passage *c*1 through each of 115 which and aligned passages in a lug 15 and member 16 extends a bolt 17 for clamping the wings and for pivotally mounting the composite needle arm in the position illustrated in Fig. 6. In this manner, the needle 120 arm may be mounted for hinging or pivotal movement and, due to the fact that the wings *c* are constructed of resilient material, said needle arm is self-restoring in the sense that, of its own volition, it tends to return to an 125 original position after being moved from such position.

Energy impulses set up by the phonograph or talking machine record are transmitted to the sound producing diaphragm by the 130

thereto-connected needle arm or stylus bar. It is highly desirable, therefore, that the latter be so constructed as to be freely vibratable in one plane, readily restorable to an original position and resistant to vibration in planes other than said one plane. A needle arm constructed and mounted as hereinbefore described and illustrated is readily movable or vibratable only in the forward and reverse direction in which it moves when moving the diaphragm 11 or the central portion thereof side-wise in either direction. In other words if the parts were positioned as illustrated in Fig. 6 the needle arm would be readily vibratable in the plane of the paper, the pivotal or hinging axis of said needle arm substantially coinciding with a line $x-x$, Fig. 8, passing through the wings c, c , at the ends of lugs 15, 15.

At the same time due to the construction and arrangement of parts the needle arm is not freely vibratable or movable in a direction longitudinally thereof, nor in that direction in which it would move under the influence of friction imposed by the record which, were the parts positioned as illustrated in Fig. 6, would be substantially at right angles to the plane of the paper. The non-vibratory or non-movable features of the needle arm noted immediately above arise largely due to the fact that the folded wings g stiffen or reinforce the wings c and, accordingly, as illustrated in Figs. 6 and 8, the needle arm hinging or pivotal axis defined by the line $x-x$ constitutes only small exposed surfaces of the wings c . The other portions of said wing c are stiffened or reinforced as described and undesired vibratable movement is thereby largely prevented.

A needle arm or stylus bar constructed and mounted in accordance with my invention, besides possessing the desirable pivotal or hinging characteristic noted above, is of small weight, particularly the member B comprised therein, which may be formed of suitable elastic or resilient material, as steel or bronze having a thickness of 0.008 of an inch, more or less. Due to this feature, the moment of inertia about the axis $x-x$ is small and, as a result, the quality of sound production is improved. At the same time, due to the angular construction comprising the walls a, a and connected base section, the member B is sufficiently stiff and does not substantially flex or give.

It is highly desirable that the connecting tie member b be formed integrally with the needle arm proper, or the part B thereof, and this may readily be accomplished by forming the member b by the same die structure that forms the blank B. Moreover, since the material forming the blank B is very thin, it follows that the mass of the tie member b is kept small, this being highly desirable.

The tie member may lead direct to the diaphragm or, preferably and as illustrated, the connection may be circuitous and comprise a U-shaped bend b_1 , or equivalent, by virtue of which the flexibility of the tie connection is improved. It should also be noted that there is a portion b_2 of the tie member b beyond the walls a, a substantially in alignment with the base between said walls and that, during a period of sound production, flexing or giving action in the needle arm proper largely occurs in said portion b_2 .

With the two-piece construction comprising the members B and B1, the latter, ordinarily, is formed from material having a thickness of the order of 0.014 of an inch, more or less, this being thicker than the material from which member B is formed although said thicker material, preferably, is otherwise similar to that from which the member B is formed. With material of such thickness for member B1, an efficient thread may be produced for the screw h by virtue of which the stylus or needle is firmly held in position on or in the needle arm. Moreover, with the two-piece construction illustrated, the hinge wings, namely, the wings c, c are formed from the material having the lesser thickness, this, of course, being desirable where an efficient hinge joint is desired. Still further, the reinforcing or stiffening members for the wings c, c , namely, the wings g, g are formed of material having the greater thickness and this, too, is desirable from the reinforcing viewpoint.

To further enhance the freedom with which the needle arm pivotally moves in the desired direction, as aforesaid, material may be removed from the axis $x-x$. In the example shown, this result is attained by forming, during the stamping operation, a plurality of openings or holes e_2 in those regions of the wings c destined to fall within the aforesaid axis $x-x$.

In Fig. 10, there is illustrated another form of my invention wherein the hinge wings y, y corresponding with the aforesaid wings c, c are formed separately from, and not integral with, the needle arm proper and particularly the member Y thereof, the latter otherwise corresponding with the aforesaid member B. As was the case with the wings c, c , the wings g, g after they are folded around the ends of the respective wings y, y serve to reinforce or stiffen said wings y, y , but with the construction illustrated in Fig. 10, said folded wings g, g also have the function of retaining the wings y, y in their proper positions on or with respect to the needle arm proper. It shall be understood that the wings y, y of the construction illustrated in Fig. 10 may be mounted on the sound box cap 13 in the same manner as are the wings c, c , Figs. 6 and 8. Obviously, with a construction such as illustrated in Fig. 10, the wings y, y may be

formed of very thin material while at the same time, the member B1 associated therewith may be formed of material of any suitable thickness.

- 5 It will be observed that the hinge wings *c*, *c* which are formed integrally with the member B are disposed on opposite sides thereof and equal distances from the diaphragm 11. Preferably, said wings *c*, *c* are 10 placed in a single plane disposed substantially at right angles to the plane of the diaphragm 11 which, in the example illustrated is a plane passing between the rings 12, 12. The same is true of the wings *y*, *y* which are 15 formed separately from the member Y. This feature is of distinct importance since, with constructions of the character illustrated, the diaphragm velocity, i. e. sidewise vibration, is largely or substantially independent 20 of deflection or bending of the needle arm hinge wings, a condition which is not satisfied when said hinge wings are disposed in a plane substantially parallel with the plane of the diaphragm.
- 25 Although the formation of the completed members B and B1 has been described as following a particular sequence of steps, it shall be understood that any desired sequence of steps may be followed and that, if desirable 30 and advisable, the structures illustrated in Figs. 3 and 4 may be produced from the respective structures illustrated in Figs. 1 and 2 by performing all of the folding operations substantially simultaneously. Moreover, forming dies, not shown, usually are 35 utilized to bring the blanks to their proper configurations.

Although the aforesaid members, structures, bars or arms have been illustrated and 40 described as operated by a phonograph or talking machine record, it shall be understood that my invention is not to be thus limited. Thus, for example, said members, structures, bars or arms may be magnetically 45 actuated, the needle or stylus, in such case, being omitted.

Still further, although the hereinbefore described members, structures, bars or arms have been specifically referred to for diaphragm-actuating purposes, it shall be distinctly understood that my invention is not to be limited to such an arrangement. Thus, for example, said members, structures, bars, or arms, actuated or vibrated by a stylus or 50 needle, or otherwise as desirable, may be utilized to transfer impulse energy to the vibrating element or to serve as the vibrating element of any device for which they are adapted, particularly devices which vibrate 55 in accordance with sound.

What I claim is:

1. A vibratable member for transmitting energy impulses from one region to another, said member comprising a body portion 60 formed from a plurality of shaped structures

of sheet material having different thicknesses.

2. A vibratable member for transmitting energy impulses from one region to another, said member comprising a plurality of shaped structures of sheet material, one of 70 said structures comprising a plurality of wings forming a hinge.

3. A vibratable member for transmitting energy impulses from one region to another, said member comprising a plurality of shaped structures of sheet material, each of 75 said structures comprising a plurality of wings, one set of said wings forming a hinge.

4. A vibratable member for transmitting energy impulses from one region to another, said member comprising a plurality of shaped structures of sheet material, each of 80 said structures comprising a body portion having lateral wings.

5. A vibratable member for transmitting energy impulses from one region to another, said member comprising a plurality of shaped structures of sheet material, each of 85 said structures comprising a body portion having lateral wings, the wings of one structure reinforcing the wings of another structure.

6. A vibratable member for transmitting energy impulses from one region to another, said member comprising a plurality of shaped structures of sheet material, each of 90 said structures comprising a body portion having lateral wings, the wings of one structure being folded about the wings of another structure.

7. A vibratable member comprising a body portion having lateral wings, and a reinforcing member of sheet material overlying a portion of each of said wings.

8. A vibratable member comprising a body portion having lateral wings, and reinforcing members of sheet material overlying portions of both sides of each of said wings.

9. A vibratory device comprising a shaped sheet metal structure having a pair of laterally extending wings for mounting said device, a portion of said wings being reinforced to increase rigidity but leaving a narrow transversely extending unreinforced region providing an axis of oscillation for said device.

10. A vibratory device comprising an elongated sheet metal member of U-shaped cross section having laterally extending wings, and a second elongated metal member having a portion of U-shaped cross section fitting 110 within said first member and having laterally extending portions reinforcing said wings.

11. A vibratory device comprising a sheet metal member of U-shaped cross section having laterally extending wings, and a second sheet metal member having a U-shaped portion fitting within said first member and a needle holding portion.

12. A vibratory device comprising a sheet metal member of U-shaped cross section hav-

ing laterally extending wings, and a second sheet metal member having a U-shaped portion fitting within said first member, a needle holding portion, and laterally extending wings secured to and reinforcing the wings on said first member.

In testimony whereof I have signed this specification this 27th day of September, 1928.
